UNITED STATES PATENT OFFICE.

FLORICEL A. ROJAS, OF NEW YORK, N. Y.

RHEOSTAT.

Application filed November 18, 1921. Serial No. 516,134.

To all whom it may concern:

Be it known that I, FLORICEL A. ROJAS, a citizen of the Republic of Santo Domingo, residing at New York city, in the county of Bronx, State of New York, have invented certain new and useful Improvements in Rheostats; and I do hereby declare the following to be a full, clear, and exact description of the invention, such as will enable others skilled in the art to which it appertains to make and use the same.

This invention relates to rheostats of the compressible resistance type, and has for its objects, first, to effect certain general improvements in such rheostats, and second, to adapt them for use within standard electric light sockets, in order that they may be used for dimming electric lights, regulating the current in small electrical instruments, and in general serve to control the current in all devices commonly attached to such sockets.

The resistance element of a rheostat of this type consists in general of a fibrous, non-conducting material, such as asbestos, impregnated with a powdered conducting substance, such as graphite, and held between two relatively movable members. As these members are moved toward each other the material is compressed and its resistance decreased. As the members are moved apart the material is expanded and its resistance increased.

In accordance with my Patents Nos. 1,315,579, September 9, 1919, and 1,366,945, February 1, 1921, the relatively movable members are in the form of conducting plates or electrodes to which the resistance material is secured, and is thus positively expanded as well as compressed by movement of the plates, no reliance being placed upon the resiliency of the material itself to effect expansion. It has been found that, due to the internal frictional resistance of the material itself, and the frictional resistance of the container walls, the greater part of the expansion and compression tends to take place in the material adjacent the movable plate (in practice one plate is commonly fixed and the other movable). This results in an overheating of this part of the resistance material with consequent danger of burning out. It also affects the nicety of regulation. In accordance with the present invention this objection has been overcome by increasing the proportion of conducting

material in that part of the resistance element adjacent the movable plate.

I have also noted that after long use, the infinitude of minute arcs gradually burn up the graphite powder and finally render the resistance material useless. In accordance with the present invention I have discovered that the addition of a small amount of powdered copper to the graphite cuts down this consumption, and materially increases the life of the resistance.

In rheostats of the compressible resistance type it is common to employ contact pins which extend inwardly from one or both of the plates and, by contacting with each other or with the other plate, form a shunt in parallel with the resistance which cuts out the latter, and allows full current to flow when the compression of the resistance material has reached a predetermined point. As long, however, as these contact pins pass through the resistance material itself, the active part of the resistance is that which is included between the inner ends of the pins, and that part adjacent the plates is practically dead and useless. This is a poor construction, greatly lessens the efficiency of the rheostats and increases the danger of burning out. In accordance with the present invention the shunt is completely insulated from the resistance material, so that the whole of the latter is effective until the shunt is thrown in. I have also devised means which audibly indicate when the shunt has been or is about to be closed, so that the operator knows when the resistance has been thrown out and full current is flowing.

In my Patent No. 1,366,945 I have shown external fixed resistances designed to be thrown in parallel with the rheostat. In accordance with the present invention I have provided means for adding fixed resistances in series, thus making it possible to regulate the total potential drop between the terminals of the compressible material. This becomes very desirable when the rheostat has been adapted for use within a standard electric light socket. These fixed resistances may be added in the shape of discs of refractory non-conducting material carrying imbedded particles of conducting matter, the discs being placed between the compressible resistance and one of the plates.

To design a rheostat of the compressible resistance type, so that it can be built within

a standard lamp socket, has been difficult. The very bulkiness of the resistance material which makes it safe also makes it difficult to work with when space is extremely limited. The small space permitted the resistance material within the socket is further limited by the passage of the return lead through it, and by the provision of the shunt which shall carry the full current when the conductivity of the resistance approaches full current capacity. These considerations have made necessary the provision of a thin-walled container occupying the least practicable space and shaped to accommodate both the return lead and the shunt. This container must also, of course, be non-conducting and heat-resisting. Other structural changes have been made which will be better described in connection with the accompanying drawings, which illustrate a lamp socket equipped with a rheostat in accordance with the invention. Although the drawings show a preferred embodiment other forms are, of course, possible and are to be considered as embraced within the invention as defined by the appended claims.

In these drawings Fig. 1 is a vertical section through a socket and its rheostat; Fig. 2 is a vertical section taken along line 2-2 of Fig. 1 and at 90° to the section shown in Fig. 1; Figs. 3, 4, 5 and 6 are transverse sections taken along lines 3-3, 4-4, 5-5 and 6-6 respectively of Fig. 1; Figs. 7, 8, 9 and 10 are detailed views of parts which will be described later; and Fig. 11 is a fragmentary view showing a fixed resistance disc in position.

The socket itself, which is of standard size and form, is indicated in the drawings by reference numeral 1. The socket is provided at its lower end with the usual base cup 2, adapted to be screwed upon a supporting terminal 3, from which the two leads 4 and 5 extend, and at its outer end with a threaded seat 6 for an attachment. A lamp 7 has been shown and the operation of the rheostat will be described in connection with a lamp, but its use is, of course, not so limited. This seat 6 forms one of the electrical contacts with the lamp and is insulated from the socket by means of a cylindrical wall of insulating material 8. The foregoing is common construction and is found in practically every electric light socket.

In accordance with this invention a rheostat is mounted within the socket and placed in series with the lamp. The resistance element of this rheostat comprises a compressible mixture of asbestos fibres and conducting powders which shall be discussed in detail later. It is indicated by the reference numeral 9 and is held between two relatively movable metal plates 11 and 12 and

within a container 13, preferably of enameled iron. A container of enameled metal has been found best adapted, for not only is it heat-resistant and non-conducting, but its walls can be made very thin and hence occupy a minimum of valuable space. It also has a certain flexibility and can adapt itself to slight variations of the other parts from standard size. By coating the inner walls of this container with a vitreous enamel another advantage is gained. When graphite is used as the constituent of the conducting element of the resistance, it has been noted that it tends to form a coating over the surface of the container walls, which coating being electrically conductive acts to short circuit the current around the resistance and causes trouble. Now I have discovered that if the container walls are made of glass or coated with vitreous enamel this difficulty is overcome and the graphite does not form a coating. The container 13 and the lower plate 12 are supported upon a base 14 held within the base of the socket and made of some insulating and heat-resisting material, preferably porcelain. The container 13, although of general cylindrical form, is provided at one side with a recess 15 extending radially inward and beyond the vertical axis of the container, as is clearly shown in Fig. 6. The walls defining this recess do not extend the entire height of the container, but terminate slightly above a half way point, as shown in Figs. 1, 2 and 10. The function of this recess is to house the other lead and the shunt, which is thrown in parallel with the resistance when the conductivity of the latter approaches full current capacity, and to insulate them completely from the resistance material. Secured to the lower face of the upper plate 11 is a block 16 of non-conducting heat-resisting material, preferably porcelain, which extends downwardly and is designed to fit within the recess 15 and exclude the resistance material. This block is provided with a boss 17 which extends through a central aperture in the upper plate 11. The block 16 is secured to the plate 11 by means of a metal screw 18, which makes electrical contact with the plate 11, the block being countersunk at 19 to provide a cavity, the function of which will be described later. The block 16 is also provided with a passageway 21, which coincides with the vertical axis 21 of the container 13. The position of block 16 within recess 15 prevents rotation of plate 11, as will be evident.

The seat 6 for the lamp is provided with an externally threaded, depending extension 22 of smaller diameter. Within this extension is mounted a block 23, preferably of porcelain, which forms the base of the lamp seat. The lower end of this block 23 projects slightly beyond the extension 22 for a

purpose which will be apparent later. Contact with the lower lamp terminal must be made at the center of this base and the block 23 is therefore provided with a central aperture 25 through which a metallic pin 24 is passed. This pin extends loosely through the passage 21 in the block 16 and through a central aperture 25 in the base 14. Here it terminates in a metal plate 10 and makes contact with the lead 4. The base 14 is provided at one side with a pin 26, which extends upwardly through the lower plate 12, making electrical contact therewith and into the recess 15. The lower end of this pin 26 bears against a plate 20 and makes contact with lead 5. Pin 26 is situated directly below pin 18, as is clearly shown in Fig 1, but is normally spaced therefrom. Pin 26 thus serves to limit the downward movement of the plate 11.

An internally threaded collar 27 is mounted upon the extension 22. This collar 27 is composed of inner and outer concentric members, 28 and 29 respectively, spaced apart by a sheet of insulating material 31. The inner member 28 must be made of metal and makes electrical contact with the extension 22. The outer member 29 is generally made of metal and for this reason must be insulated from the inner member, but it is, of course, clear that the outer member might be made of any suitable material. Surrounding the collar 27 is a chain 32. This chain is secured at its middle to the collar at 33 and extends a full turn in both directions about the collar, the two ends finally emerging together through an opening 34 in the socket. This collar 27 bears against the upper face of the plate 11, the inner member 28, making electrical contact therewith, and downward movement of plate 11 and compression of the resistance material is effected through movement of this collar. Upward movement of the plate and expansion of the adhering resistance material is effected by means of an expansion coil spring 35 encircling pin 24 and bearing upon both base 14 and block 16.

The operation of the device acting as an electric light dimmer is as follows: When the lamp 7 is in position, as shown, and the leads 4 and 5 connected to a source of electrical energy, the path of the current is through lead 4, plate 10, pin 24, the lamp, seat 6, extension 22, inner member 28 of the collar 27, plate 11, resistance material 9, plate 12, pin 26, plate 20 and lead 5. As is well understood, the conductivity of the resistance material 9 varies directly with its density. If, therefore, the chain 32 is pulled so as to cause the collar 27 to move downwardly, the plate 11 is moved toward plate 12, the material 9 is compressed and its conductivity increases. This means that more and more current is allowed to pass through the lamp filament and the light grows

brighter and brighter. Continuing the movement of collar 27 in a downward direction a point is reached when the head of screw 18 makes contact with the upper end of pin 26, which has entered countersink 19. This immediately shunts the current through these elements and makes it unnecessary for the resistance to carry the whole load. By adjusting the space between the head of screw 18 and the upper end of pin 26 relative to the resistance of material 9 it will happen that the resistance of this material will permit the flow of sufficient current for practically full luminosity at the time the shunt circuit is thrown into parallel. This means that when contact is made the light gives a small flicker which indicates that full current is flowing. This flicker is but slight and unobjectionable and is in no sense a jump, as would be the case were the resistance of material 9 considerably greater when contact is made. When the rheostat is used to regulate the current flowing through the filament of an electric lamp, the flicker is probably sufficient indication that full current is flowing. When, however, the attachment is an iron or a heating pad, means should be provided which shall give audible indication. One such means comprises a short strip of metal 36 secured to the lower face of block 16 and extending within the line of pin 26. This strip of metal is designed to snap within a small cavity 37 at the side of pin 26 at the time that contact with screw 18 is made, this snap being distinctly audible.

If the other end of chain 32 is pulled so that the collar 27 moves upwardly the spring 35 will force plate 11 away from plate 12, and as the resistance material is firmly secured to both plates it is positively expanded and its conductivity drops. As a result the current passing through the filament decreases and the light is dimmed. By continuing the upward movement of the collar 27 a point will be reached when upward movement of the plate 11 will be arrested by block 23. Further turning of collar 27 breaks its contact with plate 11 and the light is extinguished. This break should come when the conductivity of the resistance material has been reduced so low that the lamp filament is barely glowing. The light is therefore very gently extinguished. By providing stops which shall limit the upward movement of the collar shortly after contact is broken, the operator will be apprised of this fact when working with an attachment which does not glow and hence give visible indication that the current is approaching zero.

I have found that a mixture of equal parts of asbestos fibre, and powdered graphite, forms an excellent compressible resistance material. It has been found, however, as stated above, that after several

years' usage the infinitude of minute arcs tend to consume the graphite particles and that the resistance material deteriorates. I have found that if the graphite is mixed with copper powder in the proportions of about 98 parts of graphite to 2 parts of copper, this consumption of the graphite is lessened and the life of the material is greatly prolonged. The addition of a small quantity of calcium carbonate is also helpful.

As stated above, where only one of the contact plates is movable, the effect of the pull upon the resistance material immediately adjacent that plate is greater than upon that adjacent the stationary plate, the resistance of the container walls and the internal resistance of the material itself preventing uniform transmission of the pull to all parts of the material. This means that with a uniform mixture the potential drop is greater in the upper half than in the lower when the material is expanded. This, of course, prevents a regulation as delicate as that which might be obtained with a uniform potential and results in overheating of the upper part of the resistance material. It has been found that this difficulty can be obviated by making that half of the material contacting with the movable plate richer in conducting material than that half contacting with the stationary plate. For example, where powdered graphite is used as the conducting material and asbestos fibre as the non-conducting and yieldable material, that half of the resistance element contacting with the movable plate is composed of asbestos fibre, four parts, and graphite powder, seven parts, while the other half is composed of equal parts of fibre and graphite.

In Fig. 11 a fixed resistance element in the form of a disc 38 has been shown. This disc may be made of any comparatively refractory, non-conducting paste or cement in which conducting material is imbedded. By placing it upon the lower plate 12 and securing it to the resistance material any number of volts may be dropped before the current enters the resistance and thus a heat loss which might be injurious to the compressible material can be dissipated in the fixed resistance. For example, by the use of such a disc it would be possible to burn a 110 volt lamp on a 220 volt circuit.

It is desirable that such a disc have a zero temperature coefficient. Carbon having a negative coefficient, its conductivity increasing with increase in temperature, and metals having a positive coefficient, a mixture of carbon and metals can be made, the conductivity of which shall be substantially unaffected by temperature changes. However, the rate at which the conductivity of metals changes with temperature is much less than the rate of change for

carbon, and for this reason in a mixture of carbon and metals having a zero coefficient, the metal constituent must largely predominate. This is objectionable because a predominance of metals tends to short-circuit the rheostat, and because no easily oxidizable metals can be used, and the cost of those relatively non-oxidizable metals, such as copper, silver, gold, platinum, etc., is prohibitive. If a non-oxidizable, inexpensive material could be found having a high negative coefficient, and which would not tend to short-circuit the rheostat, such a material would be much superior to metals in making a mixture of zero coefficient. Such a material is crystalline, or conductive silicon. I therefore make this disc of a mixture of carbon in any of its allotropic forms with crystalline, or conductive silicon, imbedding the mixture in any relatively refractory non-conducting cement. A satisfactory composition for this purpose is, stated in approximate proportions:

Silicon 8 parts by weight.

Graphite 2 parts by weight.

Cement 4 parts by weight.

It is, of course, obvious that the compressible resistance can similarly be made of a substantially zero temperature coefficient by the addition of conductive silicon. Thus, a material analogous to the above but substituting asbestos for cement would have a substantially zero-temperature coefficient.

A satisfactory adhesive for use in attaching the resistance material to the plates is a mixture of a heavy oil and a powdered graphite, although, of course, other conducting adhesives or mechanical means might be employed. The adhesion of the resistance material to the plates is essential to the operation of the rheostat, as without this, the resistance, although it can be decreased by compression, cannot well be increased. It has been found that the resistance material adheres best to iron, the slight oxide film probably serving successfully to anchor the adhesive.

There is, of course, the usual heat loss when current passes through the compressible resistance material, the loss being at its maximum when the conductivity of the resistance equals that of the external resistance, such as a lamp filament. For high and low resistances this loss is very little. Even at its maximum, however, the heat generated is successfully radiated, so that the heating of the socket is not excessive. Nevertheless, I have found it best to provide the leads 4 and 5 with an asbestos covering for the first few inches of their length. This heating of the resistance material expands it, increases the contact among the conducting particles, and thus decreases the resistance of the whole. In my Patent 1,366,945, I have disclosed certain thermostatic means for com-

pensating for this change in resistance. In the present structure the metal rod 24 and the enamelled iron container 13 act as thermostats. With rise in temperature the rod 5 expands and thus increases the distance between plates 11 and 12 while the expansion of the container tends to close in upon the recess 15 and increase the volume of the resistance material. These changes can be 10 made to compensate for the expansion of the resistance material and the resulting decrease in its resistance.

This rheostat is free from many of the defects of others of the compressible resistance type. Unequal expansion of the material is compensated for; deterioration of the material through consumption of graphite is lessened; and a shunt is provided which is completely insulated from the material. It 15 has also been successfully adapted for use within a standard electric light socket and provided with simple means for effecting compression and expansion of the material, for indicating when full current is flowing 20 and when the current has been cut off. This rheostat is also peculiarly adapted for use in connection with dimming individual electric lights. The current can be accurately controlled and with such a nicety that no steps 25 whatever are noted as the light is turned up or down. The entire mechanism having been successfully mounted within a socket of standard size, is therefore a decided improvement over those devices which require special 30 sockets. Furthermore, this device requires no special lamp, but operates on any of the incandescent electric lamps now on the market. Each rheostat is, of course, designed for a lamp of a given wattage, the resistance 35 of the resistance material when half compressed being equal to the resistance of the lamp filament. Lamps of higher wattage may, however, be used without immediate danger of burning out, and in this respect 40 the rheostat of the present invention possesses an advantage over the wire coil rheostats employed for similar purposes. Lower powered lamps may also be employed without sacrificing the use of the lowest lights. It is obvious, however, that its use is not confined 45 to electric light dimming. It may well be employed for many and various purposes.

Although one preferred embodiment of the invention has been shown and described it is 50 clear that other forms might be devised which would operate perhaps equally well. The invention is therefore not limited by the precise structural details shown and described.

60 I claim:

1. A rheostat comprising the combination of a movable member and compressible resistance material secured to said member, the conductivity of the resistance material 65 immediately adjacent the member being nor-

mally greater than that of the rest of the material.

2. A rheostat comprising the combination of a stationary member, a movable member, and compressible resistance material between 70 said members and secured thereto, the conductivity of the resistance material adjacent the movable member being normally greater than that of the material adjacent the stationary member. 75

3. A rheostat comprising the combination of a stationary member, a movable member, and a compressible resistance material comprising a non-conducting fibrous material impregnated with conducting material between 80 said members and secured thereto, the ratio of conducting to non-conducting material being higher adjacent the movable member.

4. A rheostat comprising the combination 85 of a stationary member, a movable member, and a compressible resistance material comprising asbestos fibre impregnated with powdered graphite between said plates and secured thereto, the ratio of graphite to asbestos in that part of the resistance material adjacent the movable member being about seven to four, and that in the part adjacent the stationary member being about one to one. 90

5. A rheostat comprising the combination of two iron plates and a compressible resistance material between and adhering to said plates. 95

6. A compressible resistance material comprising a non-conducting fibrous material impregnated with powdered carbon and powdered copper. 100

7. A compressible resistance material comprising a non-conducting fibrous material impregnated with a mixture of powdered graphite and copper. 105

8. A compressible resistance material comprising a non-conducting fibrous material impregnated with a mixture of powdered graphite, copper and calcium carbonate. 110

9. A compressible resistance material comprising asbestos fibre impregnated with powdered carbon and powdered copper.

10. A compressible resistance rheostat 115 provided with means for audibly indicating when the resistance of the material has reached a predetermined point.

11. A rheostat comprising the combination of a compressible resistance material, means for compressing said material to vary its resistance, a shunt designed to be thrown in parallel with the resistance material when the resistance of the latter has reached a predetermined point, and means audibly indicating when the shunt has been thrown in. 120

12. A rheostat comprising the combination of a compressible resistance material, means for compressing said material to vary its resistance, and a shunt designed to be 125 130

- thrown in parallel with the resistance material when the resistance of the latter has reached a predetermined point, said shunt being completely insulated from the resistance material.
13. A rheostat comprising the combination of a compressible resistance material held between two conducting members, a container for the resistance material, means for moving one of the members to vary the density and resistance of the resistance material, and a shunt outside of the container which is thrown in parallel with the resistance material when the resistance of the latter reaches a predetermined point.
14. A rheostat comprising the combination of a compressible resistance material held between two conducting members, a container for the resistance material, means for moving one of the members to vary the density and resistance of the resistance material, a recess in the container from which the resistance material is excluded, a pin in said recess extending inwardly from one of the members and making electrical contact with the other member when the resistance of the resistance material has reached a predetermined point.
15. A rheostat for use in dimming electric lights comprising the combination of a compressible resistance material, means for varying the density of the material to vary its conductivity and control the current passing through the filament of the lamp, and means indicating when the light is burning at its intended brightness.
16. A rheostat for use in dimming electric lights comprising the combination of a compressible resistance material, means for varying the density of the material to vary its conductivity and control the current passing through the filament of the lamp, and a low resistance shunt which is thrown in parallel with the resistance material when the conductivity of the latter has been increased to permit substantially maximum brilliancy, the slight increase in current flow upon closing of the shunt resulting in a slight flicker in the light.
17. A rheostat comprising a compressible resistance material, two relatively movable members between which the resistance material is held and a disc of fixed resistance interposed between one of the members and the resistance material.
18. The combination of an electric light socket, a rheostat within the socket, comprising a compressible resistance material, and a thin-walled, non-conducting, heat-resisting container for the resistance material.
19. The combination of an electric light socket, a rheostat within the socket comprising a compressible resistance material, and a vitreous-enameled metal container for the resistance material.
20. A compressible resistor, comprising a container and a compressible resistance within the container made up of a non-conducting material and carbon, the side walls of the container being faced with a material to which the carbon will not adhere to form a conducting coating.
21. A compressible resistor, comprising a container and a compressible resistance within the container made up of a non-conducting material and carbon, the side walls of the container being faced with vitreous material.
22. In an electric light socket, the combination of two leads from the socket to a source of electrical energy, a rheostat of compressible resistance material within the socket and included in circuit with one of the leads, an extension of the other lead passing through the resistance material.
23. In an electric light socket, the combination of two relatively movable plates within the socket, a compressible resistance material between the plates, a screw-threaded collar bearing against one of the plates, and means for rotating the collar to move the plate and compress the resistance material.
24. In an electric light socket, the combination of two relatively movable plates within the socket, a compressible resistance material between the plates, a screw-threaded collar, means constantly urging one of the plates toward the collar, and means for rotating the collar to move the plate and compress the resistance material.
25. In an electric light socket, the combination of two contact terminals for an attachment plug, an extension on one of the terminals, a movable collar mounted on said extension, two relatively movable plates within the socket, a compressible resistance material between the plates, one plate contacting with the collar, a fixed conductor leading from the other terminal and through the resistance material but insulated therefrom, leads from the socket electrically connected with the second plate and the fixed conductor respectively, and means for moving the collar to compress the resistance material and vary its conductivity.
26. In an electric light socket, the combination of a screw-threaded seat for an attachment plug constituting one terminal, a centrally located pin constituting the other terminal, a compressible resistance material electrically connected with the seat, leads from the socket electrically connected with the resistance material and the pin respectively, and means for varying the density of the resistance material to vary its conductivity.
27. In an electric light socket, the combination of two terminals for making electric contact with an attachment plug, one of said terminals being directly connected with

an outside lead, an extension on the other terminal, a movable member on said extension electrically contacting therewith, two relatively movable plates, compressible resistance material between and adhering to said plates, the said movable member electrically contacting with one plate, means for moving the movable member in one direction to move its plate and compress the resistance material, means for causing the plate to follow the movable member when the latter is retracted to expand the resistance material, and means for breaking contact between the movable member and its plate when the conductivity of the resistance material reaches a predetermined point.

28. In an electric light socket, the combination of two terminals for making electric contact with an attachment plug, one of said terminals being directly connected with an outside lead, an extension on the other terminal, a movable member on said extension electrically contacting therewith, two relatively movable plates, compressible resistance material between and adhering to said plates, the said movable member electrically contacting with one plate, means for

moving the movable member in one direction to move its plate and compress the resistance material and pins on the two plates extending toward each other and designed to contact when the conductivity of the compressible resistance material has reached a predetermined point.

29. The combination of an electric light socket designed to hold a lamp or other attachment, and a compressible resistance rheostat within the socket in series with the lamp or other attachment, the other lead being a metallic pin passing through the rheostat, said pin acting as a thermostat compensating for the expansion of the resistance material with heat.

30. A rheostat comprising the combination of a compressible resistance material, means for compressing said material to vary its resistance, a shunt designed to be thrown in parallel with the resistance material when the resistance of the latter has reached a predetermined point, and means audibly indicating when the resistance of the material has reached a predetermined point.

In testimony whereof I affix my signature.
FLORICEL A. ROJAS.
